THREAD CONTROL MECHANISM FOR
SEWING MACHINES

Norman V. Christensen, Chicago, Harold J. Le Vesconte, Western Springs, and Albert M. Schweda, Chicago, Ill., assignors to Union Special Machine Company, Chicago, Ill., a corporation of Illinois

Application December 9, 1940, Serial No. 369,248

34 Claims. (Cl. 112—248)

This invention relates to thread control mechanism for sewing machines, and has reference more particularly to rotary mechanism for controlling the needle thread of lock stitch sewing machines.

With rotary needle thread take-ups as heretofore ordinarily constructed, much difficulty has been experienced with entanglement and winding up of the threads, in the event of breakage, either upon the take-up rotors or upon their supporting or actuating shafts, the correction for which was not only tedious but consumed a great amount of time. A further drawback of the usual forms of takeups is that their action upon thin threads or cheap threads of low tensile strength is too severe, with resultant causation of frequent ruptures, particularly when the sewing machines are run at the high speeds now considered essential in various lines of manufacture.

The chief aim of our invention is to overcome the foregoing drawbacks. This objective we realized, as hereinafter more fully disclosed, through provision of a simple and reliable take-up mechanism wherein a pair of guard plates interiorly of the path or orbit of a revolving thread-pulling element having a uniform angular velocity, confine the thread so that, in the event of its rupture, it cannot possibly become entangled with or wound upon said element or the spindle or shaft which carries it; and wherein a pair of stationary guides external to said path or orbit are so disposed relative to each other and a fixed thread detaining element extending crosswise between the plates, as to make possible the use of a rotor of comparatively small diameter and correspondingly small inertia, to facilitate quick starting and stopping of the sewing machine, and moreover, as to determine taking-up of the thread in considerably less than a semi-rotation of the take-up element compensatively with the release of the thread as the latter passes about the non-rotating bobbin holder of the rotary hook of the sewing machine to the end that strain on the thread is reduced to a minimum. The control mechanism of our invention is thus especially adapted for use with sewing machines whereof the rotary hooks make several revolutions incident to each stitch-forming cycle.

Another object of our invention is to attain these advantages in a take-up in which the shaft of the rotor is driven from the needle actuating shaft of the sewing machine, but so positioned in the needle head as to make possible the use of bearings for the needle bar above and below the

region of its connection to the actuating means therefor.

Other objects and attendant advantages will appear from the following detailed description of the attached drawings, wherein

Fig. 1 is a view, partly in side elevation and partly in longitudinal section, of a lock stitch sewing machine conveniently embodying the needle thread controlling mechanism of our invention.

Fig. 2 is a fragmentary view corresponding to Fig. 1, drawn to a larger scale and showing the needle head and a portion of the underlying work support of the machine in section.

Fig. 3 shows the left hand end elevation of the machine with a portion of the work support broken away and in section.

Fig. 3a is a view like Fig. 3 with the take-up slightly further advanced in its rotation.

Fig. 4 is a fragmentary view of the needle head of the machine with the cover thereof removed to expose the parts at the interior.

Fig. 5 is a fragmentary detail view in plan looking as indicated by the angled arrows V—V in Fig. 3.

Figs. 6, 7, 8, and 9 are views like Figs. 3 and 3a, but showing the rotary take-up in different successive positions during the stitch-forming cycle.

Fig. 10 is a fragmentary view corresponding to Fig. 8 and drawn to a larger scale.

Fig. 11 is a fragmentary sectional view taken as indicated by the angled arrows XI—XI in Fig. 5.

Fig. 12 is a perspective view of a bearing block forming one of the component parts of the needle thread control.

Figs. 13 and 14 are detailed sectional views taken as indicated respectively by the angled arrows XIII—XIII and XIV—XIV in Fig. 3, and showing the thread tensioning means of the machine which assists in controlling the needle thread.

Figs. 15, 16, 17, and 18 are perspective views of other component parts of the thread control mechanism.

Fig. 19 is an exploded view of the parts which constitute the thread tensioning means shown in detail in Figs. 13 and 14.

Figs. 20 and 21 are perspective views of upper and lower plate components which together form the needle head cover of the machine.

Figs. 22, 23 and 24 are views generally like Figs. 2, 3, and 4 showing an alternate embodiment of our invention; and,

Figs. 25, 26, and 27 are perspective views of in-

dividual component parts of the alternative construction.

The lock stitch sewing machine, which we have chosen for convenience of exemplifying our improved needle thread control mechanism in Figs. 1-10, is shown as having a base 1 whereof the horizontal top plate 2 constitutes the work support. Integrally formed with the work support 2 at one end, is a hollow standard 3 which sustains a hollow overhanging arm 4, the latter terminating at its free end in a head 5 whereof the cover plate consists of separately removable upper and lower sections 6, 7 which are secured by screws 8, 9 respectively. The needle 10 of the machine is fixed in the lower end of a vertical bar 11 guided for up and down movement in bearings 12, 13 respectively, see Figs. 2, 4 and 11, at the top and bottom of the needle head 5. Through a pitman 14, the needle bar 11 is coupled with a counterbalanced actuating crank 15 at the left hand end of a horizontal shaft 16 which extends through the overhanging arm 4 and is journaled in fore and aft bearing sleeves 17 and 18, respectively, set into a cross partition 19 at the needle head 5 and in the outer wall 20 of the standard 3, where said shaft protrudes and carries a combined hand and belt wheel 21.

Arranged to cooperate with the needle 10 in stitch formation is a rotary hook 22 of well-known construction, with a rotating component 23 having at its periphery a beak 24 for seizing loops L of the needle thread T and a non-rotating component or bobbin case holder 23x from which the bobbin thread B emerges at one side, see Fig. 3. The rotating component 23 of the hook 22 is secured by set screws 25 to the outer end of a horizontal shaft 26 which is journaled in a fixed bearing sleeve 27 beneath the work support 2. At its right hand end, the shaft 26 extends into a small housing 28 whereof the side walls are integrally formed with and depend from the work support 2, and whereof the bottom 29 is removably secured by screws 30. Fixed on the hook shaft 26 within the housing 28 is a spur gear 31 which meshes with a larger spur gear 32 on another horizontal shaft 33 which is likewise rotatably supported beneath the work support 2, the ratio of said gears being in the order of one to two. As shown in Fig. 1, the shaft 33 extends rearward through a bearing sleeve 35 into a downward prolongation 36 of the standard 3 which latter is closed at the bottom by a removable plate 37 secured by screws 38. Within the standard 3, the shaft 33 is operatively connected to the upper or needle-actuating shaft 16 through a train of spur gears 39, 40 and 41, the ratio of which is such that said shafts are rotated in unison and in the same direction. The housing 28 and the pendant portion 36 of the standard 3 are filled with oil to the levels indicated in Fig. 1, for the automatic lubrication of the gears within them. The non-rotating component 23x of the hook 22 has a recess 43 at the top of its face flange engaged by a lug on a detaining finger 45 secured to the underside of the work support 2, see Fig. 3, and is thereby prevented from rotation with the rotating component 23. Incident to being sewed in the machine, the fabric F being sewed is progressed transversely of the work support 2 by means of a four motion feed dog 46 whereof the actuating mechanism is generally designated by the numeral 47 in Figs. 2 and 3. This mechanism may be of the construction shown in U. S. Patent No. 2,035,508, granted to George Sauer et al, on March 31, 1936, and since this mechanism, per-

se, does not form part of the present invention it need not be further referred to herein. The toothed projections of the feed dog 46 operate upwardly through slots in a throat plate 48 set into the top of the work support 2 and react upon a presser foot 49 which is pivoted to a shank member 50 at the lower end of a vertical presser bar 51, and which, as ordinarily, extends upward into the needle head 5 for confinement to vertical reciprocation. Within the needle head 5 the bar 51 is surrounded by a helical spring 52 which tends to maintain the presser foot 49 yieldingly in contact with the top surface of the work progressed in the machine by the feed dog 46 in the usual manner, said spring pressing downward upon a collar 53 affixed to said bar. The presser bar 51 is held against rotating through engagement of a lateral projection 54 on the collar 53 within a vertical guide slot 55 at one side of the needle head 5. Slidingly mounted on the presser bar 51 beneath the collar 53 with provision normally of a clearance between it and the latter collar as shown, is a second collar 56 which likewise has a lateral projection 57 extending out through the vertical guide slot 55 in the needle head. The collar 56 also has an inward projection 58 (Figs. 2 and 14) which, through a link 59, is coupled with a lever 60 which is fulcrumed to rock about a screw stud 61 at the back of the needle head 5. By means of a drop link 62 (Fig. 3) the lever 60 may be connected to a suitable actuating knee press or foot treadle (not illustrated). Through the means just described, the presser foot 49 can be elevated when desired for convenience of initially inserting the work beneath same. In addition, the machine is provided with a finger latch 63 which is pivoted on a screw 65 and which has a cam portion 67 within the vertical slot 55 in the rear of the needle head 5 (see Fig. 4) bearing against the bottom of the projection 57 on the collar 56. Thus when the latch 63 is swung upward from the position shown in Fig. 3, the presser foot 49 is raised clear of the work and so temporarily locked.

Having thus described the sewing machine insofar as deemed necessary, we will now proceed to the description of the needle thread control mechanism with which our invention is more especially concerned. As shown, this mechanism includes a needle thread take-up rotor in the form of a disc 70 at the outer end of a short horizontal shaft or spindle 71 which extends into the needle head 5 and which is journaled in a bearing block 72. In the present instance, the bearing block 72 is made as a separate part and is secured within the top of the needle head 5 by a pair of screws 73. Affixed to the inner end of the spindle 71 is a spur gear pinion 75 which meshes with a drive pinion 76 on the needle actuating shaft 16 in the interval between the crank member 15 and the bearing 17, the ratio of the gears being such that the disc 70 is rotated in unison with said needle actuating shaft but in the opposite direction. If desired, the bearing 72 may be integrally formed with the frame of the machine, and, as shown, has axially-aligned bosses at opposite ends thereof, the boss at the left hand end extending outward through a clearance opening 74 in the upper section 6 of the needle head cover plate. Access may be had to the needle operating mechanism simply by removing the lower head cover section 7 only. Associated with the disc 70 and positioned immediately forward thereof, is a pair of substantially-circular stationary coaxial guard plates 75 and 76 which are laterally spaced to provide a

narrow interval 79 for passage between them of the needle thread, said plates lying wholly within the path or orbit of a lateral projection in the form of a lug 80 at the edge of said disc. This lug 80 which constitutes the needle thread pulling element of the take-up, overhangs, i. e. extends beyond the outer end of the spindle or shaft 71, and during the taking-up of the needle thread in a manner later on explained, travels about the peripheries of the guard plates 77 and 78. Inward of the lug 80 and in radial alignment therewith (see Fig. 15), the disc 70 is formed with an opening for the purposes of dynamic balance. For the sake of greater compactness of the take-up, the disc 70 is recessed at the front, see Figs. 2, 5 and 15 to accommodate the guard plate 77, which, at the lower part of its periphery has a cam edge 81 of substantially 90° extent operative upon the needle thread T in a manner also hereinafter explained. The guard plate 77 is secured to the frontal guard plate 78 at a point below the axis of the take-up disc 70 by a small segmental connecting lug 82 adjacent the periphery of the two plates, which lug operates as a thread detaining element within the path or orbit of the lug 80 on said disc and which may be integrally formed with the guard plate 78 as shown in Fig. 17. The frontal guard plate 78 is truncated or cut away at the bottom along an inclined line as at 83, and provided with a lateral shank 85, which, as shown in Figs. 5 and 17, is offset at 86 to clear the projection 80 on the disc 70 and secured to the needle head 5 by a pair of screws shown at 87 in Fig. 3.

Enroute from a suitable source of supply, not illustrated, the needle thread T first passes through a fixed guide 88 which is separately illustrated in perspective in Fig. 18, said guide having three spaced vertically-arranged apertures for passage of the thread in the manner shown in Figs. 3 and 6-9, and being formed with a lateral lug 89 for attachment to the needle head 5 by the lower of the two screws 87. From the guide 88 the needle thread T passes to a tension device 90.

As shown in detail in Figs. 13, 14 and 19, the tension device 90 includes a mounting component 91 with a tubular body from which extends laterally intermediate its ends, a sectoral flange 92 having an arcuate slot 93 concentric with the body axis. The rear end of the body of the mounting component 91 passes with a snug fit, see Figs. 13 and 14, into an aperture 94 in the lower section 7 of the needle head cover, and said mounting component is secured, with capacity for rotative adjustment, by a cap screw 95 whereof the shank passes inwardly into said cover section. The tension device 90 further includes a tubular stud component 96 (Fig. 19) whereof the inner end portion has a circumferential groove 97 which is engaged by a set screw 98 (Figs. 13 and 14) threaded laterally into the body of the mounting 91. Immediately outward of its rear end portion, the stud 96 has a diametrically-reduced smooth cylindrical intermediate portion 99, and beyond the latter, a threaded outer end portion 100 with a diametral slot 101 which extends longitudinally inward to a point within the confines of said intermediate portion. Freely rotatable on the intermediate portion 99 of the stud 96 is a pair of opposed tension discs 102 and 103 between which the needle thread T is adapted to reeve; and bearing against the outer disc 103 is a dished friction washer 105 with a diametral cross bar 106 engaged in the slot 101 of said stud. In compression between the friction washer 105 and an adjustable abutment nut 107

on the threaded outer end of the stud 96 is a tapered helical spring 108 whereby the inner tension disc 102 is yieldingly maintained in frictional contact with the outer end of the mounting component 91. At the smaller end of the spring 108, the wire of the latter is bent inwardly as at 109 in Fig. 13, to engage the slot 101 of the stud 96. The bore in the body of the mounting component 91 is enlarged as at 110 for reception of a helical spring 111 which surrounds the inner portion of the stud 96. At the inner end of the spring 111, the wire of the latter is bent inwardly as at 112 for anchorage in a radial socket hole 113 in the stud 96, while the outer end of the spring wire is extended at a tangent and formed with a rounded loop terminal as at 114 for service as a yielding check finger to act upon the needle thread T in a manner presently explained. The check finger 114 passes outward through a segmental notch 115 in the outer edge of the body of the mounting component 91 by which its motion is limited, and normally bears against the shoulder 116 of said notch as shown in Fig. 14. Accordingly, the tension of the spring check finger 114 can be regulated upon loosening the set screw 98 and rotatively adjusting the stud 96 in the mounting component 91. On the other hand, by rotative adjustment of the mounting component 91 and incidental shifting of the stop shoulder as permitted by the clamp screw 95, the upper limit of movement of the check finger 114 may be varied as desired or required to suit the action of the take-up disc 70. Freely slideable endwise in the bore of the stud 96 is a round-ended pin 117 whereof one end is adapted to engage the cross bar 106 of the friction washer 105 and the other end to be engaged by a sloping cam surface 118 on the collar 56 which is slidable on the presser bar 51, see Fig. 14. Thus as the presser bar 51 is lifted to elevate the presser foot 49, the pin 117 is thrust outward to move the friction washer 105 away from the tension discs 103 and thereby release the tension on the needle thread T.

Upon leaving the tension device 90, the needle thread T passes under a hooked regulating guide 120 which is located below the axis of the take-up disc 70 beyond the guard plates 77, 78 and the path or orbit of the lug 80 on said disc and in a vertical plane containing the axis of the needle 10. As shown, the guide 120 has a shank which extends inward through a vertical slot 121 in the lower section 7 of the needle head cover and is secured in a receiving bore in the collar 53 on the presser bar 51 by means of a set screw 122, see Figs. 2, 4 and 14. From the guide 120, the needle thread T passes upward between the guard plates 77, 78 and over the segmental lug 82 as shown in Figs. 2 and 3, then laterally to a stationary guide 123 likewise beyond the path or orbit of the lug 80 on the take-up disc 70. As shown, the guide 123 is adjustably secured by a screw 124 to a lateral extension 125 of the upper needle head cover section 6 below the axis of the rotor, and from thence the thread next passes downwardly to a guide 126 adjustably secured by a screw 127 to the lower needle head cover section 7 at the bottom, and finally to the eye of the needle. It is to be especially noted from Fig. 3a that the thread detaining lug 82 lies substantially in a radial line a-c extending from the axis of the take-up disc 70 to the eye of the guide 123 and that the guide 120 lies in a radial line a-b at an angle A substantially less than 90° from the line a-c.

The operation of the thread control mechanism with the disc 70 revolving at half the speed of the rotary hook 22, but in the same direction, is as follows: In Fig. 3, a stitch forming cycle is being initiated with the beak 24 of the rotary hook 22 about to enter the stitch loop L of the thread T thrown out by the needle 10 as the latter begins its ascent, the take-up lug 80 on the disc 70 having already entered the large supply loop L' defined jointly by the guides 120 and 123 and held from dropping from between the guide plates 18 and 19 by the detaining element 82. Such entry of the take-up lug 80 is made possible through outward displacement of the ascending limb of the thread supply loop L' by the deflecting cam segment 81 on the plate 77 to permit passage of said lug behind said limb as shown in Fig. 3a. During continued rotation of the hook 22, the needle thread loop L is carried downwardly about the non-rotating component 23x by the action of the beak 24 in the usual way, with attendant absorption of the slack provided by the supply loop L' as shown in Fig. 6. In Fig. 7 the needle thread stitch loop L has just passed about the lowest point of the non-rotating hook component 23x after having robbed the supply loop L' substantially of its slack, and said loop has just been engaged by the lug 80 on the take-up disc 70. In Fig. 8, the disc 70 is somewhat further advanced in its rotation, and has taken up most of the excess in the needle thread loop L which now completely envelops the bobbin thread B as more clearly shown in Fig. 10. After this the take-up action continues until its culmination in Fig. 9 when the take-up lug 80 reaches a position in a radial line R-R passing through the axis of the disc 70 and bisecting the angle formed in the contracted needle thread supply loop L' as a consequence of the allocation of the guides 120 and 123 as shown. The setting of the stitch is cushioned by the action of the check finger 114 as a length of thread sufficient for the next stitch is drawn off by the advance of the fabric F by the feed dog 46. From the time of initial engagement of the lug 80 with the portion of the thread T which extends between the loop detaining element 82 and the guide eye 123 in Fig. 6 to the point of complete take-up in Fig. 9, the disc 70 moves substantially through an arc of 145 degrees. The take-up action is thus completed well within the period available for that action, which period begins when the needle thread stitch loop L passes the lowermost point of the non-rotating component 23x of the hook 22 and which ends with entry of the needle into the fabric F in the formation of the succeeding stitch. From Fig. 9 it will be apparent that sufficient time is allowed for this action even if the fabric being sewed is of extreme thickness. The foregoing timing is made possible through location of the detaining element 82, the guides 120, 123 and the cam segment 81 on the guide plate 77 relative to each other and to the path or orbit of the lug 80 on the disc 70. In this connection it is also important to note that the diameter of the disc 70 is such that the needle thread is taken up compensatively with release thereof by the rotary hook as the latter completes its rotation from the position in which it is shown in Fig. 7 through the position of Fig. 8 to that shown in Fig. 9. The proper functioning of the take-up is dependent, of course, upon the resistance imposed upon the needle thread by the tension 90 and the check finger 114 both of

which can be accurately regulated to suit the particular thread being used through the hereinbefore described provisions made for their adjustment. It is, furthermore, to be noted that by disposing the disc spindle 71 to one side of the needle actuating shaft and driving it from the latter through the spur gears 75 and 76, it is possible to employ a full length needle bar 11 with a guide bearing therefor at the top of the needle head. Attention is especially directed to the fact that at the time of stitch setting in Fig. 9, the lug 80 on the disc 70 occupies a position in its orbit directly above the regulating guide element 120 so that the segment of the thread extending between said lug and said element is substantially vertical. It therefore follows from this that the amount of thread given up to the take-up will be in direct proportion to variations in the thickness of the material being sewed in the machine and by virtue of the mounting of the regulating guide element 120 on the presser bar 51 in the vertical line of the needle axis.

In the alternative embodiment of our invention illustrated in Figs. 22-27, the take-up disc 70a has a forwardly-extending circumferential flange 130 with an annular groove 131 and radially-aligned needle thread-engaging lugs 80a respectively at opposite sides of the groove. Cooperative with the disc 70a at one side of the top of the latter is stripper element 132 which has a tapered finger 133 extending into the groove 131. As shown in Figs. 23 and 26, the attaching projection 134 of the stripper is provided with a transverse slot 135 for passage of the shank of a securing clamp screw 136 which engages into an upward projection 137 on the upper needle head cover section 6a. As a consequence of this construction, the stripper 132 can be adjusted circumferentially of the take-up disc 70a within the range of the slot 135. In all other respects, the construction of the modification is identical with that of the first-described embodiment of our invention. Accordingly, in order to preclude the necessity for repetitive description, all corresponding parts in the modification are identified by the same reference characters previously employed. Incident to the operation of the modification, the needle thread T, after having been taken up to the proper extent, is stripped from the lugs 80a on the disc 70a by the inclined outer edge of the stripper finger 133 in a manner which will be readily understood from Fig. 23, the cycle of operation being otherwise the same as in the first described embodiment. Obviously by shifting the position of the stripper 132 circumferentially of the disc 70 as provided for by the slot and screw connection at 135, 136 the instant of release of the needle thread T can be timed to a nicety when the machine is initially set up, or as may be required subsequently to adapt the machine for use of needle threads of different kinds or gauges for proper coaction to the take-up with the rotary hook.

From the foregoing it will be seen that both forms of our improved thread control mechanism are simple in construction, and can be depended upon for reliability in operation. In each case, the guard plates definitely confine the thread, and in the event of rupture prevent it from becoming entangled with or wound upon either the take-up disc or the shaft therefor. In each instance moreover, the rotor is of comparatively small diameter and hence has little inertia. Ac-

cordingly it offers negligible resistance to quick starting and stopping of the machine.

Having thus described our invention, we claim:

1. Needle thread control means for a lock stitch sewing machine having a rotary hook with a rotating loop seizing component and a non-rotating bobbin thread housing component within the rotating component, said thread control means being disposed above the hook and including a pair of vertically arranged guard plates between 10 which the thread passes enroute to the needle; a take-up element which revolves about the peripheries of the guard plates; a pair of thread guides exteriorly of the guard plates; and a loop stop extending crosswise of the plates adjacent 15 their peripheries, said guides and stop being all disposed below the rotative axis of the take-up element and cooperating to define and retain a supply loop of the needle thread in the interval between said plates.

2. Needle thread control means according to claim 1, including means whereby the take-up element is revolved at half the speed of the rotary hook; and wherein the thread guides are so spaced that the taking up of the thread is accomplished in less than a semi-revolution of the take-up element about the guard plates.

3. Needle thread control means according to claim 1 including means whereby the take-up element is revolved at half the speed of the rotary hook; wherein the thread guides are so spaced that the taking up of the thread is accomplished in less than a semi-revolution of the take-up element about the guard plates; and wherein a stationary means laterally deflects one limb of the loop so that the take-up element may enter it during each of its rotations, said deflecting means being also below the rotative axis of the element and so located with respect to the guides as to determine taking up of the thread during less than 40 a semi-rotation of the take-up element about said guard plates.

4. Needle thread control means for a sewing machine having a presser foot and a supporting bar therefor, said thread control means comprising a single revolving thread engaging take-up element; a pair of guides for directing the thread respectively into and out of the path of the take-up element, one of said guides being stationary and the other affixed to the presser bar for movement therewith; and means adjacent the path of the take-up element intermediate the guides for engaging the thread and predetermining the point of initial engagement of the thread by said take-up element during each stitch forming cycle of the machine.

5. Thread control mechanism for sewing machines and the like, comprising a pair of spaced stationary guard plates between which the thread passes en route to a stitch forming instrumentality of the machine; means for defining and retaining a supply loop of the thread between the guard plates; and a take-up element moving in an orbit around the peripheries of the guard plates and adapted to engage the supply loop during each rotation, said take-up element being in the form of a laterally projecting lug on a revolving disc alongside of one of the two guard plates, and said disc having its face recessed to accommodate such guard plate.

6. Thread control mechanism for sewing machines and the like, comprising a pair of spaced stationary guard plates between which the thread passes en route to a thread manipulating instrumentality of the machine; means for defining and

retaining a supply loop of the thread between the guard plates; a take-up element revolving about the peripheries of the guard plates; and means in the form of a segmental cam projection on one of the guard plates for laterally deflecting one limb of the supply loop to permit the element to enter the loop during each rotation.

7. Thread control mechanism for sewing machines and the like, comprising a pair of spaced stationary guard plates between which the thread passes en route to a thread manipulating instrumentality of the machine; a take-up element revolving about the peripheries of said guard plates; means for defining and retaining a supply loop of the thread between the guard plates including a pair of thread guides externally of said plates, and a loop stop which extends crosswise of said plates adjacent their peripheries, said thread guides and loop stop being all disposed to one side of the rotative axis of the take-up element; and means for laterally deflecting one limb of the supply loop to permit entry of said element into the loop during each rotation, said deflecting means being in the form of a segmental cam projection on one of the guard plates located at the same side of the rotative axis of the take-up element as the thread guides and the loop stop.

8. Thread control mechanism for sewing machines and the like, comprising a pair of spaced stationary guard plates between which the thread passes en route to a thread manipulating instrumentality of the machine; means for defining and retaining a supply loop of the thread between the guard plates; a take-up element revolving about the peripheries of the guard plates and adapted to engage the supply loop during each rotation; and stationary stripper means adjustable peripherally of the guard plates for dislodging the loop from the take-up element at the completion of each take-up cycle.

9. Thread control mechanism for sewing machines and the like, comprising a pair of spaced stationary guard plates between which the thread passes en route to a thread manipulating instrumentality of the machine; means for defining and retaining a supply loop of the thread between the guard plates; a take-up element revolving about the peripheries of the guard plates and adapted to engage the supply loop during each rotation, said take-up element being in the form of a laterally projecting lug on a revolving disc alongside one of the guard plates; and stationary stripper means in the form of a finger which projects into an annular groove in the face of the disc for dislodging the loop from the take-up element at the completion of each take-up cycle.

10. Rotary needle thread take-up mechanism for lock stitch sewing machines, including a rotary thread engaging and manipulating element; a thread tension disposed between a thread supply and said element; a thread detaining means adjacent the orbit of said element for determining the point of engagement thereof with said thread; and a thread deflector disposed between said detaining means and said tension, said deflector being constructed and arranged to engage the bight of thread extending between said thread detaining means and said tension and to distend the thread beyond the path of travel of the thread engaging and manipulating element.

11. Thread control mechanism for sewing machines and the like, comprising a take-up element which moves in an orbit in a vertical plane

above the point of stitch formation in the machine to measure a definite length of thread in excess of the amount required for each stitch and to take up such excess to set the stitch at the end of each stitch forming cycle; and a regulating element actuated by changes in the thickness of the material being sewed to compensatively regulate the amount of thread being measured each time, said regulating element being so disposed relative to the orbit of the thread take-up element that the latter is substantially in a vertical line with said regulating element and the point of stitch formation at the time of stitch setting.

12. In a sewing machine having a needle and a presser foot, thread control mechanism comprising a take-up element which moves in an orbit in a vertical plane above the point of stitch formation in the machine to measure a definite length of thread in excess of the amount required for each stitch and to take up such excess to set the stitch at the end of each stitch forming cycle; and a regulating element connected to the presser foot for actuation thereby incident to changes in the thickness of the material being sewed to compensatively regulate the amount of thread measured, said regulating element being so disposed relative to the orbit of the thread take-up element that the latter is substantially in a vertical line with said regulating means and the point of stitch formation at the time of stitch setting.

13. In a sewing machine having a vertically reciprocating needle, thread control mechanism comprising a take-up element which moves in an orbit in a vertical plane above the point of stitch formation in the machine to measure a definite length of thread in excess of the amount required for each stitch and to take up such excess to set the stitch at the end of each stitch forming cycle; and a regulating element in line with the axis of the needle and actuated by changes in the thickness of the material being sewed to compensatively regulate the amount of thread measured, said regulating element being so disposed relative to the orbit of the take-up element that the latter is substantially in a vertical line with said regulating element and the point of stitch formation at the time of stitch setting.

14. Thread control mechanism for sewing machines and the like, comprising a thread engaging take-up element which moves in an orbit in a vertical plane above the point of stitch formation in the machine to measure a definite length of thread in excess of the amount required for each stitch and to take up the excess to set the stitch at the end of each stitch forming cycle; and a thread guide by which the thread is directed into the orbit of the take-up element actuated by changes in the thickness of the material being sewed to compensatively regulate the amount of thread measured each time, said guide being so disposed relative to the orbit of said take-up element that the latter is substantially in a vertical line with the guide and the point of stitch formation at the time of stitch setting.

15. In a sewing machine having a vertically reciprocating needle, thread control mechanism comprising a take-up element which moves in an orbit in a vertical plane above the point of stitch formation in the machine to measure a definite length of the thread in excess of the amount required for each stitch and to take up such excess to set the stitch at the end of each stitch forming cycle; a thread tension through which thread passes en route from a source of supply; a thread

guide which receives the thread from the tension and directs the thread into the orbit of the take-up element; and means for actuating the thread guide in accordance with changes in the thickness of the material being sewed to compensatively regulate the amount of thread measured each time, the guide being so disposed relative to the orbit of the take-up element that the latter is substantially in a vertical line with said guide and the point of stitch formation at the time of stitch setting.

16. Needle thread control mechanism for a sewing machine having a work support, comprising a thread engaging take-up element disposed above said work support for movement in an orbital zone of operation; a vertically movable thread guide disposed between said zone and said work support for directing the thread into said zone; a second thread guide disposed laterally and externally of said zone for determining the point of exit of the thread from said zone en route to stitch forming instrumentalities associated with said work support; and thread detaining means positioned intermediate said thread guides for engagement by the thread and operative to determine the point of initial engagement of said thread by said take-up element incident to the formation of a stitch.

17. Needle thread control mechanism for a sewing machine having a work support, comprising a thread engaging take-up element disposed above said work support for movement in an orbital zone of operation; a vertically movable thread guide disposed between said zone and said work support for directing the thread into said zone; a second thread guide disposed laterally and externally of said zone for determining the point of exit of the thread from said zone en route to stitch forming instrumentalities associated with said work support; and thread detaining means positioned intermediate said thread guides within the area surrounded by said zone and arranged to be engaged by the thread to determine the point of initial engagement of said thread by said take-up element incident to the formation of a stitch.

18. Needle thread control mechanism for a sewing machine having a work support, comprising a thread engaging take-up element disposed above said work support for movement in an orbital zone of operation; a vertically movable thread guide disposed between said zone and said work support for directing the thread into said zone; a second thread guide laterally and externally of said zone adapted to determine the point of exit of the thread from said zone en route to stitch forming instrumentalities associated with said work support; thread detaining means intermediate said thread guides arranged to be engaged by the thread to determine the point of initial engagement of said thread by said take-up element incident to the formation of a stitch; and means within said zone for restraining the thread against excessive movement transverse to its path of travel during the action of said take-up element.

19. Needle thread control mechanism for a sewing machine having a work support, comprising a thread engaging take-up element disposed above said work support for movement in an orbital zone of operation; a vertically movable thread guide disposed between said zone and said work support for directing the thread into said zone; a second thread guide laterally and externally of said zone adapted to determine the point of exit of the thread from said zone en route to stitch forming in-

strumentalities associated with said work support; thread detaining means intermediate said thread guides and arranged to be engaged by the thread to determine the point of initial engagement of said thread by said take-up element incident to the formation of a stitch; and a pair of spaced guard elements positioned within said zone for restraining the thread against excessive movement transverse to its path of travel during the action of said take-up element.

20. Needle thread control mechanism for a sewing machine having a work support and stitch forming instrumentalities associated with said work support, comprising a take-up element arranged to move in a circular orbit above said work support, said element being spaced radially from and overhanging the end of a rotatable supporting and actuating shaft; a vertically movable thread guide disposed between said work support and said orbit for directing the thread en route from the supply across and within said orbit; a second thread guide laterally of and external to said orbit for directing the thread out of said orbit en route to said stitch forming instrumentalities; and a thread detaining means adjacent said orbit and intermediate said guides, arranged to position the thread for initial engagement by said take-up element incident to the formation of a stitch.

21. Needle thread control mechanism for a 30 sewing machine having a work support and stitch forming instrumentalities associated with said work support, comprising a take-up element arranged to move in a circular orbit above said work support, said element being spaced radially from and overhanging the end of a rotatable supporting and actuating shaft; a vertically movable thread guide disposed between said work support and said orbit for directing the thread, en route from the supply, across and within said orbit; a second thread guide laterally of and external to 40 said orbit for directing the thread out of said orbit en route to said stitch forming instrumentalities; a thread detaining means adjacent said orbit and intermediate said guides arranged to position the thread for initial engagement by said take-up element incident to the formation of a stitch; and a pair of spaced guard elements within the orbit of the take-up element for restraining the thread against excessive movement laterally of its path of travel while said thread is being acted upon by said take-up element.

22. Needle thread control mechanism for a sewing machine having a work support and stitch forming instrumentalities associated with said work support, comprising a take-up element arranged to move in a circular orbit above said work support, said element being spaced radially from and overhanging the end of a rotatable supporting and actuating shaft; a vertically movable thread guide disposed between said work support and said orbit for directing the thread, en route from a supply, across and within said orbit; a second thread guide laterally of and external to said orbit for directing the thread out of said orbit en route to said stitch forming instrumentalities; thread detaining means adjacent said orbit and intermediate said guides, arranged to position the thread for initial engagement by said take-up element incident to the formation of a stitch; and a thread tension device adapted to engage said thread in advance of its engagement by said first-named thread guide.

23. Needle thread control mechanism for a sewing machine having a work support and stitch

forming instrumentalities associated with said work support, comprising a take-up element which is arranged to move in a circular orbit above said work support, said element being spaced radially from and overhanging the end of a rotatable supporting and actuating shaft; a vertically movable thread guide disposed between said work support and said orbit for directing the thread, en route from the supply, across and within said orbit; a second thread guide disposed laterally of and external to said orbit for directing the thread out of said orbit en route to said stitch forming instrumentalities; and a thread detaining element positioned between the orbit of said take-up element and the axis of said rotatable shaft and lying approximately in a radial line which extends through the axis of said shaft and said second thread guide.

24. Needle thread control mechanism for a 20 sewing machine having a work support, comprising a thread engaging take-up element disposed above said work support and arranged to move in a circular orbital zone of operation; a vertically movable thread guide disposed between 25 said zone and said work support for directing the thread into said zone; a second thread guide disposed laterally and externally of said zone for determining the point of exit of the thread from said zone en route to stitch forming instrumentalities associated with said work support, said second thread guide lying in a radial line which extends through the axis of said zone at an angle of less than ninety degrees from a radial line containing said first-named thread guide; and stationary thread detaining means within said zone adapted to be engaged by said thread, and thereby to determine the point of initial engagement of said thread by said take-up element.

25. In a sewing machine, a thread take-up device comprising, adjacent thread-engaging members rotatable in a common plane about a common axis spaced a substantial distance from said members, said members having leading and trailing edges, said members being spaced one from the other on a common radius and providing therebetween an arcuate thread-removing element clearance slot concentric with the paths of rotation of said members, and a thread-removing element extending transversely of said plane and disposed to traverse said slot in the rotation of said members.

26. In a sewing machine, a rotary thread take-up means having an orbital path of rotation, said means being spaced substantially from its axis 55 of rotation and having a leading thread engaging edge substantially radial to said axis, said means being provided between the radially outer and inner faces thereof with a passage extending depthwise across the plane of rotation of said means, and a thread-removing element extending transversely of said plane of rotation of said take-up means and disposed to traverse said passage in the rotation of said means.

27. In a sewing machine, a thread take-up device comprising, a disk rotatable about a fixed axis, thread-engaging means extending from a side face of said disk with all portions thereof eccentric to said axis and adapted to effect a take-up action on a thread by engaging and shifting a bight of said thread in a plane parallel to the face of said disk, said means being provided in the end face thereof opposite to said disk with a thread-removing element clearance passage, and a thread-removing element extending transversely of said side face of the disk and disposed

to traverse said passage in the rotation of said means.

28. In a sewing machine, a thread take-up device comprising, a disk rotatable about a fixed axis, thread-engaging means extending from a side face of said disk with all portions thereof eccentric to said axis and adapted to effect a take-up action on a thread by engaging and shifting a bight of said thread in a plane parallel to the face of said disk, said means being provided in the end face thereof opposite to said disk with an arcuate thread-removing element clearance passage having said axis as its center of curvature, and a stationary thread-removing element disposed to traverse said passage in the rotation of said means.

29. In a sewing machine, a rotary thread take-up member carrying projecting means having an orbital path of rotation, said projecting means being spaced substantially from its axis of rotation and having a leading thread engaging edge substantially radial to said axis, said projecting means being provided between the radially outer and inner faces thereof with a passage extending depthwise across the plane of rotation of said projecting means, means for confining the thread for engagement by said projecting means, and a thread-removing element disposed to traverse said passage in the rotation of said projecting means.

30. In a sewing machine, a thread take-up device comprising, a disk rotatable about a fixed axis, thread-engaging means extending from a side face of said disk with all portions thereof eccentric to said axis and adapted to effect a take-up action on a thread by engaging and shifting a bight of said thread in a plane parallel to the face of said disk, said means being provided in the end face thereof with a thread-removing element clearance slot extending depthwise transversely of said face of said disk, means complementary to said disk for confining the thread for engagement by said means, and a thread-removing element disposed to traverse said slot in the rotation of said means.

31. A rotary take-up for the needle thread of a sewing machine having a reciprocating needle which comprises a disk mounted on the needle head and rotated in timed relation with the reciprocation of the needle, means projecting laterally from said disk and carried thereby through an orbital path, all portions of said means being spaced a substantial distance from the axis of rotation of said disk and being arranged to engage the needle thread and shift the same in a plane parallel to the face of the disk to effect a take-up action thereon upon each revolution of said disk, and means serving to remove thread engaged with said projecting means including an arcuate passage formed in said projecting means concentric with said orbital path and a stationary member projecting into the plane of said projecting means and arranged to traverse said arcuate passage upon each revolution of said disk.

32. A rotary take-up for the needle thread of a sewing machine having a reciprocating needle which comprises a disk mounted on the frame of the machine above the point of stitch formation, means for rotating said disk in timed relation with the reciprocations of said needle, a plurality of thread engaging elements projecting laterally abruptly from said disk and so disposed thereon as to be carried in orbital paths incident to the rotation of said disk, means within and without said orbital paths for positioning a needle thread enroute from a source of supply to the point of stitch formation for periodic engagement by said thread-engaging elements, said elements being elongated circumferentially of said orbital paths and being spaced along a line radial to said paths to provide adjacent parallel wall portions forming an arcuate clearance passage open at the outer ends of said elements and concentric with said orbital paths, and a stationary thread engaging member in fixed relation to said frame, said member including a thread-engaging portion extending in a direction parallel to the axis of rotation of said disk and so positioned as to traverse said clearance passage incident to the rotation of said take-up elements.

33. A rotary take-up for the needle thread of a lock stitch sewing machine comprising a rotatable shaft carried by the needle head of the machine, a disk secured to said shaft adjacent the free end of said needle head, means providing a pair of thread engaging elements projecting laterally from said disk and movable in an orbital path incident to the rotation of said disk, said elements having leading and trailing thread retaining edges and being spaced from each other in a radial direction with respect to said orbital path and providing an arcuate passage between them which is concentric with said orbital path, thread guiding means for leading thread from a source of supply into the zone of action of said elements and from said zone to the point of stitch formation, and a stationary thread engaging member extending inwardly into the space between the orbits of said elements and arranged to traverse said arcuate passage.

34. In a take-up for a sewing machine a disk fixed to the end of a rotatable shaft, thread take-up means fixed to the face of said disk comprising a pair of circumferentially elongated, laterally extending thread engaging members provided with leading and trailing thread retaining edges, said members having adjacent faces spaced from each other and concentric with the axis of said shaft forming an arcuate slot extending depthwise parallel to said axis, and stationary means including a member having a free end terminating closely adjacent to the face of said disk and positioned to traverse said arcuate slot incident to the rotation of said disk and shaft, said means serving to remove thread engaged with said take-up means.
